PROJECTOR FOR TIME INDICATIONS

Harry B. Nasscot, Mamaroneck, N. Y.

Application February 3, 1942, Serial No. 429,403

2 Claims. (Cl. 58—50)

The invention relates to time-indicating mechanism and more especially to means in association therewith whereby a visual time indication may be momentarily displayed on the ceiling of an unlighted room in which the time mechanism or clock is located, for example, on the portion of the ceiling immediately above a bed, the display being under control of the occupant thereof; or it may be found useful during "blackouts" either for continuous or momentary display of the time indication.

The invention has for an object to provide the exhibiting element and its advancing mechanism as a cooperative but separate and distinct unit for association with time mechanism.

Another object of the invention is to so construct this unit that it may readily be disengaged from the associated driving time mechanism, as in case of repair or replacement of any parts thereof; or for removing, except during the periods of darkness, from the time mechanism the load introduced by the unit; also to allow of proper setting of the projected individual indicia with reference to the time mechanism.

Still another object is to maintain the displayed individual time indications stationary for a sufficiently long period by effecting intermittently the advance of a film bearing the same.

In carrying out the invention, a suitable casing is provided to conceal the time mechanism, which may be a clock of either the spring-actuated or synchronous-motor type, the mechanism being enclosed by the casing and only the dial with hands thereof being exposed, for example at the front. Within this casing and mounted preferably upon a swingable door member or the like, which may constitute the back of the casing, is the display mechanism which is located in such a manner that, when the door is closed, said mechanism is juxtaposed to the time mechanism for actuation thereby and also is juxtaposed to an aperture in the top of the casing for projection therethrough of the image of time indicia.

Thus, a vertically disposed optical system is provided which may move with the door or be a fixed part of the top of the casing, and the same is designed for juxtaposition to the said aperture therein. An electric lamp, also, is provided in the optical axis of the lens system, and between the same and said system is designed to be advanced an endless strip of film bearing a succession of indicia conforming to the time units as represented by the rotations of an ar-

bor driven by the clock mechanism. The arbor is designed for engagement with the driving means for the endless film strip, said engagement being effected periodically from the arbor so that an intermittent advance will be imparted to the film strip in its travel between the lens system and the lamp. The said electric lamp is designed to be momentarily energized, as through the provision of a suitable switch or button conveniently located on the casing, so as to project the indicia on the film strip upon the ceiling whenever the circuit is closed to the lamp.

Provision is also made to disengage readily the driving connection between the arbor and the drive mechanism for the film strip; and there is provided in connection with the driving connection a knob or like member located externally of the casing whereby the film strip may be set manually, when the disengagement has been effected, to conform its indicia to the time indicated by the time mechanism.

The nature of the invention, however, will best be understood when described in connection with the accompanying drawing, in which:

Fig. 1 shows the novel device in isometric projection.

Fig. 2 is a transverse section through the casing, taken on the line 2—2, Fig. 1, with the interior parts shown in end elevation; and Fig. 3 a longitudinal section taken on the line 3—3, Fig. 2 of the drawing, and looking in the direction of the arrows.

Fig. 4 is a detail, fragmentary longitudinal section illustrating the film advance disengaging and film setting arrangements.

Referring to the drawing, 10 designates a suitable casing or box for housing the clock mechanism as well as the means for projecting the time shown by said mechanism. This time mechanism is of any well-known form of clock, either spring-actuated or driven by a synchronous motor, the latter type being indicated in the embodiment shown. The said clock mechanism is indicated as a container 11 mounted within the casing 10 and has outwardly-directed arbors for the minute hand 12 and hour hand 13, as well as a second hand 14, all movable over the dial 15 at the front of the casing.

In this embodiment, the casing 10 is extended 50 backwardly to accommodate the projecting time-indication unit, the casing being provided to this end also with an aperture 20 in the top through which the indications may be projected, as hereinafter set forth. A switch element 21 is mounted at the top of the casing having a finger

portion 22 projecting through a slot 23 in said top whereby energization of an electric lamp unit 24 is controlled for the purpose hereinafter set forth. A vertically disposed optical system 25, adjustable for focussing, is carried by the top in line with the aperture and depends from the top into the interior of the casing; and the lamp unit 24 is optically aligned with said system but displaced therefrom to allow of a film strip 26 passing therebetween. This strip bears suitable indicia 27 along its length corresponding to the time units to be displayed and as determined by an arbor of the time mechanism, for example the seconds arbor 28 which is rearwardly extended from the container 11 and carries one of the elements 29 of a Geneva movement or other suitable means for imparting intermittent motion from the time mechanism to the film strip. The latter is constituted as an endless band of film or like transparent material having the indicia 27 thereon, and it is carried by a plurality of sprocket wheels or rollers 30 secured to the back 31 of the casing 10 which is hinged at the bottom as at 32. The film is engaged, also, by a further sprocket 33 which serves to advance the film intermittently in equal increments, said film being maintained under suitable tension by a tensioning roller 34 also carried by the back 31.

On the spindle 35 for said sprocket 33 and at its inner end is mounted for rotating the spindle the cooperating element 36 of the Geneva movement, whereby said film strip is advanced from the arbor 28 between the lamp unit 24 and the optical system 25, for example once every minute. The extent of this advance is made to conform to the time indications on the dial so that the respective indicia of the film strip will be positioned successively for projection by the light rays of lamp unit 24 through the optical system 25 and upon the ceiling of a room in which the device is located, provided the switch 21 has been actuated to close the circuit to the lamp unit 24.

All of the elements for mounting and advancing said film, as well as the lamp unit 24, being secured to the movable back 31, these become readily accessible when the back is swung outwardly for repair or replacement. The separation of the cooperating Geneva movement elements may be effected by so mounting the spindle 35 that it may be manually withdrawn axially outwardly, as by means of a knob 40 secured thereto externally of the casing 10. The spindle to this end is mounted in a sleeve 41 which is keyed to the spindle and over which sleeve the sprocket 33 is secured. The sleeve 41 is preferably of the split type at one end, with end prongs 42 designed to fit a notched portion 43 at the corresponding end of the spindle, when the latter is drawn outwardly, to definitely limit thereby the extent of movement. A similar notch 44 is provided in the spindle at the cooperating end

to limit, when engaged by the prongs, its movement inwardly for positioning element 36 with respect to element 29 of the Geneva movement. The foregoing arrangement, furthermore, admits of movement of the film 26 independently of the time mechanism when the spindle 35 has been drawn outwardly and the Geneva element disengaged, so that the said film may be manually set, by turning knob 40, to conform the indicia 10 to be projected to the time indications of the time mechanism.

I claim:

1. Projector for time indications, comprising a casing with aperture in the top, a vertically disposed optical system for juxtaposition to said aperture in projecting an image therethrough, an electric lamp in the optical axis of said system and means accessible exteriorly of the casing for controlling manually energization of said lamp, time mechanism located within the casing including a dial visible through the front of the casing having hands movable thereover and an arbor extending into the interior of the casing making a complete rotation in a predetermined unit of time, an endless film strip mounted for movement between the lamp and the optical system, said film bearing spaced indicia conforming to the time unit of said arbor, driving means for the strip adapted for engagement with the arbor, and manually operable means accessible exteriorly of the casing to effect engagement between the driving means and said arbor for advance of the former and to effect disengagement therewith in setting the film strip to conform the same to a time indication on the dial.

2. Projector for time indications, comprising a casing with aperture in the top and a movable back for the casing, a vertically disposed optical system for juxtaposition to said aperture in projecting an image therethrough, an electric lamp carried by the back in the optical axis of said system and means accessible exteriorly of the casing for controlling manually energization of said lamp, time mechanism located within the casing including a dial visible through the front of the casing having hands movable thereover and an arbor extending into the interior of the casing making a complete rotation in a predetermined unit of time, and a unit carried by the back comprising an endless film strip mounted for movement between the lamp and the optical system, said film bearing spaced indicia conforming to the time unit of said arbor, driving means for the strip adapted for engagement with the arbor, and manually operable means accessible exteriorly of the casing through the back thereof to effect engagement between the driving means and said arbor for advance of the former and to effect disengagement therewith in setting the film strip to conform the same to a time indication on the dial.

HARRY B. NASSOIT.
